UNITED STATES PATENT OFFICE.

ERIC A. HOLMGREN, OF EAST LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON FOOTWEAR.

Application filed September 25, 1919, Serial No. 326,178. Renewed November 9, 1926.

This invention relates to the manufacture of boots and shoes and by way of illustration is herein shown and described as embodied in a machine for forming or molding the heel 5 seats and counters of shoes. In the manufacture, for example, of shoes to which wood heels are to be attached it is common to shape the heel seat and conform the upper materials to the contour of the last by the use of a machine constructed to subject the heel seat, 10 while the shoe is on a last, to the pressure of a shaping die or block the face of which corresponds substantially to that of the upper or attaching face of a wood heel, a series 15 of manually effected hammer blows being delivered around the heel end of the shoe adjacent to the die while the shoe is so held. These blows are struck more or less glancingly away from the sole, the purpose of the glancing blows being to prevent the counter and 20 upper from being "bunched" into the rand crease. This practice not only requires considerable time of even a skillful worker, but when performed unskillfully tends to injure 25 the appearance of the shoe about the heel end rather than to improve it.

A general object of the present invention is to provide a machine capable of performing the work above described satisfactorily 30 and economically, and with this object in view the invention provides a machine having means for shaping the shoe bottom, as by holding a shoe under molding pressure at the heel seat end, and means for shaping the 35 counter and upper material at the heel end of the shoe as, for example, by a succession of rapidly repeated pressures while the molding pressure continues, for the purpose of effecting more satisfactorily, as well as more expeditiously and with less labor, the shaping 40 which heretofore required manual hammering by expert workmen. A further object is to utilize heat in this shaping operation, preferably in a novel combination including 45 movable wipers and carriers therefor in which electric heat units are mounted.

In accordance with another object of the invention, means is provided for ensuring uniform predetermined molding pressure on 50 the heel seats of lasted shoes whatever the sizes

of the lasts, said means comprising primarily a novel organization of spring-controlled toggles.

In the illustrated machine this object is accomplished by a primary toggle constructed 55 and arranged to support a work carrier, and a secondary toggle having means for yieldingly resisting breaking movement thereof, the latter toggle being so connected to the first-mentioned toggle as to yieldingly resist 60 excessive pressure transmitted through the work carrier to the primary toggle.

It is recognized that this and other features of the invention illustrated may have other uses including application to machines of 65 types other than heel seat forming machines.

These and other objects and features of the invention will be explained in the following description and the novelty then pointed out in the appended claims. 70

In the drawings,

Fig. 1 is a side elevation, partly broken out, of an illustrative machine embodying my improvements;

Fig. 2 is a view similar to the upper portion 75 of Fig. 1 on a larger scale and more extensively broken out;

Fig. 3 is a detail plan view of the molding devices and their carrier;

Fig. 4 is a front elevation, partly broken 80 out, of the parts shown in Fig. 3;

Fig. 5 is a perspective view, partly broken out, of the two mold holders with one mold 85 in place; and

Fig. 6 is a broken-away perspective view 85 of part of a mold holder with its electric heating means.

A suitable frame 12 is formed or provided with a bracket extension carrying a bearing 13 (Fig. 1) to pivotally support a lever 14, 90 said lever being pivotally connected at 15 to the lower end of the lower member of a toggle 16, the upper member of which is pivotally supported at 17.

To the knuckle 18 of the toggle is connected 95 one end of a spring 19, the other end of which is suitably secured to the frame so as to exert a constant tendency to hold the toggle 16 in the position shown in Fig. 1. Adjustably to determine the normal relative angular 100

positions of the two members of the toggle 16, the upper member is provided with an arm 20 having a screw 21 adapted to contact with an abutment 22 of the frame. By adjusting said screw the normal angular position mentioned can be regulated. It is desirable, however, to provide further means for limiting the relative positions of the two members of the toggle so that they can not assume a straight line. To this end the two members of the toggle are provided with co-acting lugs or stop members 23 which, regardless of any adjustment which may be given to the screw 21, will prevent the knuckle 18 of the toggle 15 from assuming a "dead center" position. Consequently, during operations hereinafter described, the toggle is certain to "break."

To support the last carrying a shoe during the operations hereinafter described, the jack pin 24 is carried by a swinging post. The structure of this post is best illustrated in Fig. 2. A portion of the shank of the jack pin is threaded at 25 and the lower end 26 of said shank slidably fits a socket in a post 27 which is pivotally supported at 28 as hereinafter described, so that the jack can be swung to and from the positions indicated in Figs. 1 and 2. To enable the jack pin to be vertically adjusted and at the same time 30 yieldingly supported, the threaded portion 25 engages an internally threaded upper portion of a sleeve 29 having an internal shoulder 30 arranged to co-operate with the upper end 31 of the post 27 thereby limiting downward movement of the jack pin 24. A spring 32 confined between a collar 33 of the post 27 and an internal shoulder 34 of the sleeve 29 yieldingly supports the shank of the jack pin. To prevent the said shank from rotating in the socketed post 27, its lower end is provided with a vertical groove 35 which is engaged by a screw or pin 36 mounted in the post 27.

The jack carries a toe rest as indicated 45 at 37, said toe rest being of any usual or preferred construction.

A link 38 connects the pivot 28 to a pivot pin 39 mounted in the frame, the object of this link being simply to control the vertical 50 movements of the jack pivot 28 during the operations to be described.

To raise and lower the jack, I provide a primary toggle structure comprising upper and lower members 40, 41 (Fig. 1) having 55 a knuckle connection 42, the lower member being pivoted at 43 to the outer end of lever 14 (Fig. 1). The toggle operating link 44 is pivotally connected at one end to the toggle knuckle 42 and at the other end 45 (Fig. 2) to the lower end of a lever 46 which is carried by a stud rockshaft 47 mounted in the frame, said lever 46 having a roll 48 engaging a path cam 49 in one face of a disk carried by the cam shaft 50, the latter 60 having also a driving gear 51.

It is preferable that the shaft 50 shall, when operated, come to rest at the end of a single revolution. To this end it is rotatably connected with the gear 51 by a suitable one-revolution clutch such as a Horton clutch. 70 As such devices are well known, it is unnecessary to illustrate or describe the details thereof further than to explain that the arm 52 (Fig. 1), pivoted at 53 and having a spring 54, is acted upon by means of a rod or link 55 connected with a foot lever 56, the connections of such clutch being that the operator, by depressing the lever 56, will connect the constantly rotating gear 51 to the shaft 50 so as to impart a single revolution 80 to said shaft.

Any suitable means for constantly rotating the gear 51 may be employed, such as a pinion 57 carried by a shaft 58 having a belt pulley 59. 85

When the shaft 50 revolves, its cam 49 actuates the lever 46 to impart a thrust to the link 44 so as to straighten or nearly straighten the toggle members 40, 41, and raise the jack post. At this point it is 90 advisable to explain that prior to this straightening action of the toggle the operator will have manually swung the jack from the position shown in Fig. 1 to that shown in Fig. 2 to bring the last and its shoe 95 to proper position for operation. Spring 32 serves at this time to hold the shoe up with its heel seat in contact with a die, hereinafter described, and to prevent accidental movement of the shoe after the operative has 100 brought it into the proper position. After this cam 49 is actuated to straighten the toggle 40, 41 thrusting the last and shoe forcibly against the die.

To limit the outward position to which the 105 jack may be swung, the post 27 has a lug 60 which will contact with a stop lug 61 at the outer end of link 38.

To receive the pressure when the jack is elevated by the toggle mechanism described, 110 a die or block 62 of selected shape to give the desired form to the heel seat is removably mounted in a holder 63 having a shank 64 mounted in an externally threaded sleeve 65 which is provided with an annular external 115 groove 66. A set screw 67 passes through the bearing for the sleeve 65. By rotating the sleeve 65 the height of the form block 62 relatively to the mechanism below it is adjusted and such adjustment is maintained 120 by the screw 67. To prevent rotation of the holder 63 and its form block, a pin 68 enters a recess in the holder 63, said pin being carried by a bracket 69 having a pin 70 secured in the frame 12.

A mold carrier 71 having a recessed front portion as indicated in Fig. 3 is supported by a yoke 72 (Figs. 2 and 4) which in turn is supported and actuated by parallel members one of which comprises a link 73 pivoted 130

to the yoke at 74 and to the frame at 75. The lower end of the yoke 72 is pivotally connected at 76 with an arm 77 of a rockshaft 78 mounted in the frame. Said rockshaft 5 has another arm 79 the outer end of which is ball shaped. Bearing against the under surface of the ball end 80 is a bearing collar 81 mounted on a rod 82 and adjustable thereon by set nuts 83. The upper surface 10 of the ball end 80 of the lever receives the pressure of a collar 84 slidably mounted on the rod 82 and acted upon by a spring 85, the degree of compression of which is adjustable by means of set nuts 86 on the 15 threaded upper end of rod 82.

The lower end of the rod 82 is pivoted at 87 to a lever 88 one end of which is pivotally supported on the frame pin 39, the other end carrying a roll 89 engaged in a path cam 90 20 in one face of a disk carried by shaft 50. The cam path 90 as shown has a contour capable of imparting three complete oscillations to the lever 88, while the heel-seat molding pressure is being maintained, the mold carrier 77 25 being consequently moved vertically three times in each direction during the cycle of movement.

A rockshaft 91 (Figs. 1 and 2) is provided with a downwardly extending arm 92 having 30 a tip 93 adapted to engage the tip 94 of an arm 95 of the rockshaft 47. An upper arm 96 of the rockshaft 91 is connected to the outer end of a tension spring 97 the other end of which is suitably fixedly connected to the 35 frame. The rockshaft 91 also has two other arms 98, one of which is indicated in Fig. 2, and the other of which extends in a similar direction at the other side of the machine. The two arms 98 are connected by links 99 40 (Figs. 1, 2 and 3) to the mold holders presently to be described.

As hereinbefore mentioned, the mold carrier 71 is recessed in front. The upper surface of said carrier is circularly grooved at 45 100, as indicated by dotted lines in Fig. 3, one end of said groove terminating at one side of the recess and the other terminating at the other side of the recess. This groove 100 is engaged by curved ribs 101 (Fig. 5) of the 50 two mold holders 102, said mold holders being shown in Fig. 5 as close together at their rear portions. Each link 99 is connected to a mold holder by means of a universal joint comprising a vertical pin 103 carried by the 55 mold holder 102, a coupling 104, and a horizontal pin 105 connecting said coupling with the link 99.

Each holder 102 has its lower portion longitudinally grooved at 106. The inner wall of 60 which groove 106 is engaged by a rib 107 (Fig. 5) of a mold or wiper 108, the structure being such that the two mold members, which together constitute the mold, can slide rearwardly in the holder and also laterally, 65 the latter being due to the relative width of

the grooves 106 and ribs 107. A suitable cover plate 109 secured by bolts 110 to a rear portion of carrier 71 retains the mold members or wipers in position in the holders 102. In this construction the mold holders, with 70 the mold members, constitute jaws which are opened to receive the shoe and are closed yieldingly to hold the shoe and shape the upper to the last.

Yieldingly to hold the mold members or 75 wipers toward each other in the positions shown in Figs. 3, 4 and 5, plungers 111 bear against the outer walls of the mold members, said plungers being actuated by springs 112 mounted in casings 113 carried by the holders 80 102. To limit the inner positions of the two plungers so that they will not be thrown out of their sockets or casings when the mold members are removed, the outer end of the stem of each plunger is provided with a 85 stop pin 114.

Two flat leaf springs 115 (Fig. 4 and dotted lines Fig. 3) are secured to the under surfaces of the holders 102. The free end of each spring is provided with a pin 116 the 90 upper portion of which passes through an opening in a holder 102 and extends into a lateral groove 117 formed in the under face of the mold 108. The grooves 117 are considerably wider than the diameters of the 95 upper ends of the pins 116 so that while said pins prevent the mold members from being unintentionally ejected from position, they do not interfere with rearward shifting of the molds. If it is desired to remove the mold 100 members for any purpose such as the substitution of differently shaped mold members therefor, the lower milled ends of the pins 116 are pulled down, the springs 115 yielding sufficiently, to lower the pins out of the 105 grooves 117.

To yieldingly hold the mold members or wipers 108 in the forward position which is limited by a pin 116, I provide plungers 118 mounted in rear casings 119 of the holders 110 102, springs 120 causing the plungers to exert pressure on the rear of the mold members or wipers. To retain the plungers in their sockets when the mold members are removed, suitable limiting pins 121 are carried by the 115 outer ends of the stems of the said plungers.

To adjustably limit the degree or extent of rearward motion of the mold members or wipers, in opposition to the springs 120, stop screws 122 (Fig. 3) are mounted in the carrier 71 in alignment with the rear ends of the stems of the plungers 118.

Suitable provisions are made for heating 125 the mold members and their holders, this being effected preferably by means of electric heating elements 124, which receive current through leads 125, and which are removably mounted in casings 123, one of which is carried by each of the holders 102 (Figs. 5 and 6).

In operation a shoe having its sole or outsole attached is placed upon the jack pin 24 with the toe portion supported by the rest 37, this being done while the jack support 27 is 5 swung out to the position shown in Fig. 1. The toe rest ensures support of the shoe firmly at the proper angle to provide for proper molding of the counter and upper material adjacent to the heel seat portion of the shoe. 10 The operator then swings the jack support to the position shown in Fig. 2, the heel end of the shoe passing into the recessed portions of the molding devices, the different members of which yield to accommodate the particular size or width of the rear of the shoe. 15 As hereinbefore explained the mold members 108 are interchangeably mounted. This provides for material variations of sizes. It is to be understood also, of course, that form 20 blocks or dies 62 of different sizes or forms may be interchanged, one for another, for such purposes as conforming to the sizes or styles of the different shoes to be operated upon.

25 After the jack support has been swung to the position shown in Fig. 2 the operator, by means of the foot lever 56, connects power to the shaft 50 so that the latter will be given one revolution. The relative timing positions of the cams carried by the shaft 50 are such that first, the toggle members 40, 41 are actuated toward straightened position so as to lift the shoe against the block 62. This movement is effected by means of the cam 30 49 acting upon the roll 48 of the lever 46 to impart a thrust to the link 44. This at the same time permits the spring 97 to actuate the rockshaft 91 so that, through the arms 98 and the links 99, the mold holders 102 are 35 yieldingly moved forward and toward each other on the guides provided by the curved ribs 101, so that the mold members 108 are closed and pressed against the rear end of the shoe. During further straightening 40 movement of the toggle members 40, 41 and consequent continued lifting of the shoe, the series of cam steps 90 acts upon the roll 89 of lever 88 rapidly to reciprocate rod 82. This, through the arms 79, 77 of the rockshaft 78 45 imparts a succession of up-and-down movements to the mold carrier 71. These movements of the carrier 71, although strictly in the arc of a circle on a radius equal to the length of the links 73, 77, are substantially 50 vertical because the links are long relatively to the extent of their swinging movement. Therefore, while the lasted shoe is held under molding pressure at its heel seat end, the counter and upper material at the heel 55 end of the shoe are subjected to a repeated series of pressures during continuance of the molding pressure for the reason that the mold members, as shown, are shaped to overhang the inwardly curved portions of the upper and counter adjacent to the heel-seat. 60

The vertical movements of the mold members not only cause increasing and diminishing pressure to be applied to the region of the upper and counter lying adjacent to the heel-seat, but also cause the mold members 70 to produce a heightwise wiping effect on the upper about the heel end resulting in smoothing out the wrinkles in a manner equal to that effected by the usual hammering operation when done by an expert workman as 75 hereinbefore referred to. The heating of the mold by means of heat units 124 inserted in the casings 123 aids in ironing out the wrinkles and shrinking the leather into conformation with the heel end of the last. 80

The molding pressure resulting from straightening of the toggle members 40, 41 is not materially different when lasts of different sizes are employed. This is due to the structure including the second toggle device 85 16 and the spring 19. To explain this, supposing it were attempted to impart a thrust to link 44 through the medium of a spring, this would not compensate for different angular relative positions of toggles 40, 41 due 90 to varying heights of lasts. This is of course assuming that the pivot 43 would be in fixed or unyielding position. Owing, however, to the fact that the base toggle pivot 43 is carried by lever 14 the position of which latter 95 is controlled by toggle 16 and spring 19, compensation is obtained for imparting the same amount of pressure to varying height sizes of lasts. For instance, supposing a shoe on a low last is to be operated upon so that there 100 is no occasion for the lever 14 to yield when the toggle members 40, 41 are straightened, the toggle members 16 are not affected; that is, owing to the low height of a last, no such pressure is applied as would be necessary to 105 overcome the resistance of the nearly straight toggle members 16 and the spring 19. If, however, a last of considerably greater height size is in the shoe to be operated upon, then when the thrust link 44 is actuated the toggle 110 members 40, 41 will still straighten out without crushing the last, because the pivot 43 carried by lever 14 will yield against the resistance of spring 19 transmitted by toggle 115 16. The resistance to such yielding movement remains practically constant irrespective of the extent of movement of lever 14 because the greater the movement that is imparted to lever 14, the greater is the breaking movement of toggle 16 and the increase in 120 this breaking movement compensates roughly for the increased tension of spring 19. The structure described thus provides a high degree of adaptability, sufficient practically to eliminate all danger of damage resulting 125 from excessive pressures due to unusually high lasts or other causes.

Having described my invention, what I claim as new and desire to secure by Letters Patent of the United States is:—

1. A machine of the character described having, in combination, a molding device, means for holding a shoe and said device clamped together under sustained molding pressure to mold the shoe bottom to the shape of the molding device, and means for subjecting the counter and upper material adjacent to the heel-seat of the shoe to pressure which increases and diminishes during maintenance of said molding pressure. 65
2. A machine of the character described having, in combination, a molding device, means for holding a shoe and said device clamped together under sustained molding pressure to mold the shoe bottom to the shape of the molding device, and means for subjecting the counter and upper material adjacent to the heel-seat of the shoe to pressure directed inwardly and downwardly with respect to the heel-seat, one of the components of said pressure being repeatedly increased and diminished during continuance of said molding pressure. 70
3. A machine of the character described having, in combination, a molding device, means for holding a shoe and said device clamped together under sustained molding pressure to mold the shoe bottom to the shape of the molding device, and means for subjecting the counter and upper material at the heel end of the shoe to a repeated series of pressures during continuance of said molding pressure, said pressures being exerted in a direction to iron out wrinkles in the upper material. 75
4. A machine of the character described having, in combination, a molding device, means for holding a shoe and said device clamped together under sustained molding pressure to mold the shoe bottom to the shape of the molding device, and means for subjecting the counter and upper material at the heel end of the shoe to a rapidly repeated series of pressures during continuance of said molding pressure. 80
5. A machine of the character described having, in combination, a molding device, means for holding a shoe and said device clamped together under sustained molding pressure to mold the shoe bottom to the shape of the molding device, universally mounted wipers located to act on the heel end of a shoe while under said molding pressure, and means for actuating said wipers. 85
6. In a machine of the character described, a primary toggle constructed and arranged to support a work carrier, and a secondary toggle having means for yieldingly resisting breaking movement thereof, said secondary toggle being connected to the primary toggle to yieldingly resist excessive pressure exerted through the primary toggle. 90
7. In a machine of the character described, a lever and two toggles connected to said lever, one of said toggles being constructed and arranged to support a work carrier and the other toggle having a spring constructed and arranged to offer a yielding resistance to movement of said lever. 95
8. In a machine of the character described, a member movable between work-receiving and work-presenting positions, a member against which the work is pressed, means for moving said first-named member into work-presenting position comprising a toggle through which said movement is transmitted to said member, a second toggle constructed and arranged to yield upon excessive pressure on said first-named member, and yielding means constructed and arranged normally to resist breaking movement of the second toggle, the parts of said second toggle being relatively constructed and arranged to offer decreasing resistance to breaking of that toggle to compensate for the increase in force of said yielding means upon the second toggle. 100
9. In a pressure exerting machine, a pair of relatively movable pressing members, a toggle support for one of said members, a second toggle having a spring for yieldingly opposing its breaking movement, and connections between said toggle support and said second toggle whereby excessive thrust pressure of the former will be transmitted to the latter. 105
10. In a pressure exerting machine, a pair of relatively movable compressing members, a toggle for actuating one of said members toward the other, a lever connected to the toggle to sustain it in operation, a second toggle also connected to said lever, and a spring for yieldingly opposing breaking movement of the second toggle. 110
11. In a pressure exerting machine, a pair of relatively movable compressing members, a toggle for actuating one of said members toward the other, a lever connected to the toggle to sustain it in operation, a second toggle also connected to said lever, a spring for yieldingly opposing breaking movement of the second toggle, and means for preventing the knuckle of the second toggle from assuming a dead center position. 115
12. In a pressure exerting machine, a lever, and two toggles connected to said lever, one of said toggles having a spring connected to it to oppose its breaking movement, the other toggle having a work carrying member connected to it. 120
13. In a pressure exerting machine, a lever, and two toggles connected to said lever, one of said toggles having a spring connected to it to oppose its breaking movement, the other toggle having a work compressing member connected to it, and adjustable means for variably determining the normal angularity of the two members of the toggle to which said spring is connected. 125

14. A machine of the character described having, in combination, a last supporting arm, a lever, a toggle connecting said lever and arm, means for exerting straightening action on said toggle, a second toggle connected with said lever, and a spring for yieldingly opposing breaking movement of the second toggle, said second toggle and its spring being constructed and arranged to 10 yieldingly oppose movement of said lever away from normal position.

15. A machine of the character described having, in combination, a lever, a toggle having its lower member supported by one end of 15 the lever, a last-supporting arm connected with the upper member of said toggle, a second toggle connected with the other end of said lever, and a spring for yieldingly opposing breaking movement of the second toggle.

16. A machine of the character described having, in combination, a molding device, means for holding a shoe and said device clamped together under sustained molding pressure to mold the shoe bottom to the shape 25 of the molding device, a mold carrier, a plurality of mold members shaped to correspond to the inward curve of the side of a last adjacent to the heel-seat, and means for actuating said carrier heightwise of the last 30 to cause the mold to bear repeatedly on the inwardly bent portion of the upper and counter about the heel end of the shoe during continuance of said molding pressure.

17. A machine of the character described 35 having, in combination, means for holding a lasted shoe under molding pressure at its heel seat end, a recessed mold carrier, a pair of mold members mounted to yield laterally and rearwardly in said carrier, and means for 40 actuating said carrier to cause the mold to apply increased pressure repeatedly to the portion of the upper and counter adjacent to the heel seat and to rub vertically on the heel end of the shoe during continuance of said 45 molding pressure.

18. A machine of the character described having, in combination, means for holding a lasted shoe under molding pressure at its heel seat end, a recessed mold carrier, a pair of 50 holders movably mounted on said carrier, mold members yieldingly mounted in the holders, and means for actuating the mold carrier heightwise of the shoe.

19. A machine of the character described 55 having, in combination, a vertically movable jack, a co-acting die block, a recessed mold carrier, means for raising and lowering the carrier, a pair of holders movably mounted in said carrier, molds yieldingly mounted in the 60 holders, and means for yieldingly actuating the mold holders on said carrier.

20. A machine of the character described having, in combination, a vertically movable jack, a co-acting die block, a recessed mold 65

carrier, means for raising and lowering the carrier, a pair of holders having curved guiding connections with the carrier, mold members yieldingly mounted in the holders, and means for yieldingly actuating the mold 70 holders in said carrier.

21. In a machine of the class described, in combination, a support for a shoe, a horizontal carrier and wipers sliding therein to be closed about the end of the supported shoe, and means to move the carrier away from the 75 shoe bottom with the wipers in engagement with the upper materials.

22. In a machine of the class described, in combination, a support for a shoe, a carrier and horizontal wipers angularly movable 80 therein arranged to be closed about the end of the supported shoe and moved away from the shoe bottom in engagement with the upper materials, and means to supply heat thereto to shape the upper materials by the combined 85 action of heat and rubbing pressure.

23. In a machine of the class described, in combination, a support for a shoe, a carrier and wiper plates slidably and angularly movable 90 therein to engage near the rand crease the upper materials of a shoe on the support, and means to move said carrier away from the rand crease with the wiper plates in engagement with and rubbing against the upper materials.

24. In a machine of the class described, in combination, a support for a shoe, angularly-movable members automatically to conform to and yieldingly to engage near the rand crease the upper materials of a shoe supported thereby, means to heat said members, and means to move said members away from the rand crease in engagement with the upper materials to shape them by the combined 100 action of heat and rubbing pressure.

25. In a machine of the class described, in combination, a support for a shoe, a jaw comprising wiper plates which are yieldingly movable to grip the upper materials about one end of a shoe on the support, and mechanism relatively to move the support and said jaw to rub the upper materials progressively away from the shoe bottom toward the top of the shoe.

26. In a machine of the class described, in combination, a support for a shoe, a jaw comprising a carrier and wiper plates therein which are movable to grip the upper materials about one end of a shoe on the support, heating means on the carrier to heat the wiper plates, and mechanism relatively to move the shoe support and said jaw to rub the upper materials progressively away from the shoe bottom toward the top of the shoe.

27. In a machine of the class described, in combination, a support, recessed carriers mounted on the support, yieldingly mounted shoe-engaging members slidable in the car-

riers to conform to the shape of a shoe, and electric heating units in the recesses of the carriers.

28. In a machine of the class described, in combination, a support for a shoe, plates to engage the upper materials about one end of a shoe supported thereby, and means repeatedly to rub said plates back and forth in the direction of the height of the shoe in engagement with the upper materials in both directions.

29. In a machine of the class described, in combination, a support for a shoe, plates to engage the upper materials about one end of a shoe supported thereby, means to heat the plates, and means repeatedly to rub said plates back and forth in the direction of the height of the shoe in engagement with the upper materials in both directions.

30. In a machine of the class described, in combination, normally-separated members to engage opposite sides of a shoe, a support to present a shoe thereto, means to close said members about the end of the shoe, and means to move the closed members in engagement with the upper materials of the shoe and back and forth in the direction of the height of the shoe.

31. In a machine of the class described, in combination, means to mold the heel-seat of a shoe, members to engage the counter portion of a shoe operated on thereby, and means to rub said members back and forth in constant engagement with the upper materials of the shoe.

32. In a machine of the class described, in combination, means to mold the heel-seat of a shoe, members to engage the counter portion of a shoe operated on thereby, means to heat said members, and means to rub said members back and forth in constant engagement with the upper materials of the shoe.

33. In a machine of the class described, in combination, a molding device, means to hold a shoe with its heel seat clamped constantly thereagainst under molding pressure to receive its shape therefrom and means to shape the upper materials of a shoe clamped thereby.

34. In a machine of the class described, in combination, a molding device, means to hold a shoe with its heel seat clamped constantly thereagainst under molding pressure to receive its shape therefrom, heated means, and means for actuating the said heated means repeatedly to rub and smooth the upper materials of the clamped shoe.

35. In a machine of the class described, in combination, means to shape the bottom of a shoe, heated means, and means to actuate said heated means heightwise of the shoe to rub and shape the upper materials of the shoe operated on thereby.

36. In a machine of the class described, in combination, means to shape the bottom of a

shoe, a device to shape the upper materials of a shoe operated on thereby, and cyclic mechanism to bring said means into operation and to move said device into engagement with the shoe, and thereafter to rub it back and forth in constant engagement with the upper materials of the shoe.

37. In a machine of the class described, in combination, means to jack a shoe, members to be closed about the end of a shoe jacked thereon, yielding means to close said members on the shoe, and a stop normally restraining operation of said yielding means and moved to an inoperative position by operation of the jacking means.

38. In a machine of the class described, in combination, a one-piece die to form on the heel seat of a shoe bottom a convexity to receive the cavity of a wood heel, and means to shape the upper materials of the shoe adjacent to the heel seat during the operation of the die.

39. In a machine of the class described, in combination, means to form on the heel seat of a shoe bottom a convexity to receive the cavity of a wood heel, and members movable back and forth in engagement with the upper materials of the shoe adjacent to the heel seat to rub them against an enclosed last.

40. In a machine of the class described, in combination, means to form on the heel seat of a shoe bottom a convexity to receive the cavity of a wood heel, and heated members movable back and forth in engagement with the upper materials of the shoe adjacent to the heel seat to iron them against an enclosed last.

41. In a machine of the class described, in combination, a concave mold to form a convex seat on a shoe bottom to receive a wood heel, a support to force a shoe thereagainst to mold its heel seat, and means to rub the upper materials against an enclosed last to shape them adjacent to the heel seat.

42. A machine of the character described having, in combination, a support for a lasted shoe, a heel-seat die, pressure applying mechanism operative upon one of said members to hold the heel-seat of the shoe clamped under molding pressure, jaws arranged to engage about the heel end of the shoe, and mechanism for closing the jaws to apply substantial pressure to the heel end of the shoe being molded and for opening the jaws to facilitate removal of the molded shoe.

43. A machine of the character described having, in combination, a support for a lasted shoe, a heel-seat die, normally open jaws arranged to engage about the heel end of the shoe, and interconnected mechanism for closing the jaws upon the shoe to apply substantial pressure thereto and for relatively moving the support and die to hold the heel-seat of the shoe clamped under molding pressure.

44. A machine of the character described

having, in combination, a shoe support, a heel-seat die, operating mechanism for producing pressure between said die and support, a pair of normally open jaws adapted to engage around the heel end of the shoe, and mechanism including a spring for closing the jaws yieldingly when pressure is produced by said operating mechanism.

45. In a machine for operating on the heel end of a shoe, a shoe support, a pair of jaws constructed and arranged to engage around the heel end of the shoe and for movement heightwise of the shoe, means for moving the jaws heightwise of the shoe, and mechanism for closing the jaws and holding them closed, said mechanism being unaffected by the heightwise position of the jaws.

46. A machine of the character described having a support for a shoe, a heel-seat die, the die and support being relatively movable perpendicularly to the heel-seat, mechanism for effecting such relative movement to mold the heel-seat, a shoe holder adapted to grasp the shoe adjacent to the heel-seat, and connections between said pressure mechanism and the shoe holder for opening and closing the holder as an incident to the operation of the pressure mechanism.

47. A machine of the character described having a support for a shoe, a heel-seat die, the die and support being relatively movable perpendicularly to the heel-seat, mechanism for effecting such relative movement to mold the heel-seat, a shoe holder adapted to grasp the shoe adjacent to the heel-seat, and connections including a spring by which as an incident to the operation of said operating mechanism the holder is caused to close yieldingly against the shoe with substantial pressure.

48. In a machine of the character described, a last supporting member arranged to hold a last bottom up, a rigid heel seat die formed to apply localized pressure confined to the heel seat of a shoe on said last to compress and shape the heel seat of the shoe between the last and die for the reception of a wood heel, a primary pressure exerting mechanism arranged to operate on one of said members to apply a light preliminary pressure to the work as the work is positioned, and a secondary pressure-producing device acting to effect heavy pressure of said members together.

49. In a machine for forming the heel seat of a shoe on its last for the reception of a wood heel, the combination of a last support, a heel seat die shaped to mold the heel seat of a shoe on said last to correspond to the cup of a wood heel, and a pair of devices for effecting relative movement of the last and die, said devices being constructed and arranged for successive operations, one to effect yielding preliminary pressure between the last and die and the other to augment the preliminary pressure.

50. In a machine of the class described, in combination, a support for a shoe, jaws movable to grip the upper material of the shoe at one end of a shoe on the support, and mechanism arranged to cause relative movement of the shoe support and the jaws to rub the upper material progressively away from the shoe bottom toward the top of the shoe.

51. A machine for operating upon shoes having, in combination, a support for a last, a recessed end embracing mold shaped to conform to the counter portion of the upper of a shoe, electric heating means located in the recess of the mold for heating the mold, and means for causing relative movement of the last support and the mold to cause the mold to conform the counter portion of the upper of a shoe carried by said support to the last.

52. A machine for operating upon shoes having, in combination, a support for a last, a recessed end embracing mold arranged for engagement with the counter portion of the upper of a shoe upon the last carried by the support, means in the recess of said mold for heating the mold, and means for causing relative movement of the last support and the mold to cause the mold to operate upon the counter portion of the upper of the shoe to shape and hold said counter portion to the last.

53. A machine for operating upon shoes having a mold comprising a pair of members shaped to conform to the counter portion of a shoe, said members being mounted for relative movement to position said members in accordance with the size of the shoe to be operated upon, an electric heating unit carried by each of said members, a work support arranged to carry a shoe to be operated upon, and means for causing relative movement of the mold members and a shoe upon the work support to cause the mold members to shape the counter portion of the upper of the shoe.

54. A machine for operating upon shoes having a mold comprising a pair of members shaped to conform to the counter portion of a shoe, a holder for said members arranged to permit relative movement of the mold members to position said members in accordance with the size of the shoe to be operated upon, an electric heating unit carried by each of said members, a work support arranged to carry a shoe to be operated upon, and means for causing relative movement of the mold members and a shoe upon the work support to cause the mold members to shape the counter portion of the upper of the shoe.

55. In a machine for forming the heel-seats of shoes for the reception of wood heels, the combination of a fixed heel-seat die for shaping the heel-seat only of a shoe, a shoe support, means for effecting a preliminary movement of the support for bringing the shoe and die into operative relation and for holding the shoe against accidental displacement rela-

tively to the die, and power-operated means for effecting further relative movement of the shoe support and die to effect molding of the heel-seat by the die.

5 56. In a heel-seat forming machine, the combination of a heel-seat die, a last support, a toggle for lifting the last support, means under manual control for moving the support

toward the die so that the die and support may be properly located with respect to each other and held in such relation, and power means for operating the toggle to force the shoe against the die. 10

In testimony whereof I have signed my name to this specification.

ERIC A. HOLMGREN.
